DISPENSER CABINET FOR BULK MILK AND OTHER LIQUIDS

Lannie F. Norris, Minneapolis, Minn., assignor to Norris Dispensers, Inc., Minneapolis, Minn., a corporation of Minnesota

Application March 19, 1954, Serial No. 29,612

Term of patent 14 years

(Cl. D2—3)

Fig. 1

Fig. 3

Fig. 2

Figure 1 is a perspective view of a dispenser cabinet for bulk milk and other liquids, embodying my new design;

Figure 2 is a front elevation of the same; and

Figure 3 is a side elevation of the same the other side being substantially the same as the side shown.

The essential features of my design reside in the portions shown in full lines.

I claim:

The ornamental design for a dispenser cabinet for bulk milk and other liquids, as shown and described.
